UNITED STATES PATENT OFFICE.

ROBERT H. REID, OF LAKE CHARLES, LOUISIANA.

DISPLAY-CABINET.

992,689.

Specification of Letters Patent. Patented May 16, 1911.

Application filed November 26, 1910. Serial No. 594,383.

To all whom it may concern:

Be it known that I, ROBERT H. REID, a citizen of the United States, residing at Lake Charles, in the parish of Calcasieu and State of Louisiana, have invented a new and useful Display-Cabinet, of which the following is a specification.

It is the object of this invention to provide a display cabinet for umbrellas, canes and the like, the cabinet comprising a rotatable case, and a display member rotatable in the case the display member being so constructed that it will hold and display a plurality of the devices which the cabinet is adapted to contain.

With the foregoing and other objects in view which will appear as the description proceeds, the invention resides in the combination and arrangement of parts and the details of construction hereinafter described and claimed, it being understood that changes in the precise embodiment of invention herein disclosed can be made within the scope of what is claimed without departing from the spirit of the invention.

In the drawings.—Figure 1 is a sectional elevation: Fig. 2 is a transverse section on the line 2—2 of Fig. 1; and Fig. 3 is a fragmental perspective of one of the holders, with its attendant parts.

The base upon which the cabinet, as a whole, is rotatable, comprises preferably a head 1, from which legs 2 radiate, the legs 2 being provided with casters 3. Fixed to and rising from the head 1, is a shaft 4, upon which the case 5 is rotatable. The case 5 comprises a base 6, a top 7, and frames 8, uniting the base 6 and the top 7. Other frames 8' are hinged to the frames 8, as shown at 9. The several frames 8 and 8' are equipped with transparent plates 10, whereby the contents of the structure may be examined by prospective purchasers. When the hingedly mounted frames 8', which constitute the closures of the structure, are disposed as shown in Fig. 2, and held in place by suitable locking devices 40 (Fig. 1), the case 5 will, if properly constructed, be dust proof, so that the contents thereof will be protected from deterioration.

The shaft 4 extends through the base 6 of the case, and engages the top 7 thereof, thus to provide a rotatable mounting for the case. Depending from the base 6 of the case is a bracket 11, equipped with a down-

wardly projecting, conical neck 12, adapted to register within a series of balls 13, held in a ball-race 14, formed in the upper face of the head 1.

A display member is rotatable within the case 5, this display member comprising a bottom 21, from which rises a tube 41, the tube 41 inclosing the shaft 4, to provide a rotatable mounting for the display member. Extended downwardly from the bottom 21 of the display member is a conical neck 20, adapted to be received by a series of balls 19, held in a ball-race 17, formed in the upper face of the base 6 of the case 5. Secured to, and projecting radially from the tube 41, are a series of partitions 25, defining compartments 26 in the display member. To the outer edges of the partitions 25, oppositely projecting angle members 28 are secured.

To each pair of the angle members 28, arcuate holders 29 are attached by means of removable securing devices, indicated conventionally at 31. To the outer faces of the holders 29, a series of article-holding clips 30 of any desired form are applied. These clips, as clearly shown in Fig. 3, may be arranged at different heights, thus providing for the holding of umbrellas and canes of different lengths. The articles which, at their upper ends, are retained in the clips 30 are at their lower ends, retained in openings 42 formed in the bottom 21 of the display member.

Secured to the legs 2, and projecting outwardly beyond the base 6 of the case 5, are a plurality of arms 32, having a function to be explained hereinafter.

In practical operation, a quantity of canes or umbrellas may be mounted in the compartments 26, and it may be noted that the holders 29 constitute partial closures for the compartments, so that the articles therein may not readily be displaced. The canes or umbrellas which are to be displayed most prominently, are engaged at their upper ends by the clips 30, their lower ends being mounted in the openings 42 in the bottom 21. The umbrellas or canes which are thus held, may readily be observed through the transparent plates 10 of the case 5, and by rotating the case 5, any one of the movable closures 8' may be positioned opposite any one of the holders 29, so that a given umbrella or cane may readily be removed. By the same process, access may be had to the

articles which are stored in the compartments 26. As one umbrella after another is examined by the purchaser, the umbrella may be rested upon the floor, and against the case 5, the umbrella being prevented from falling over, by the arms 32 which outstand beyond the case 5.

Having thus described the invention, what is claimed is:—

- 10 1. A device of the class described comprising an outer, rotatably mounted case; a display member rotatable in the case and comprising a bottom and radially extended partitions defining a plurality of compartments in the display member; holders secured transversely to the outer edges of the partitions, to serve as partial closures for the compartments; and clips outstanding from the holders; the bottom being provided with elements coöperating with the clips in holding the articles which the device is to display.
- 15 2. A device of the class described comprising a base; a shaft rising therefrom; a case rotatable upon the shaft; a display member rotatable in the case and comprising a bottom, a tube rising from the bottom and inclosing the shaft, partitions secured to and radiating from the tube; holders disposed transversely of the partitions and secured 30 to the edges thereof, adjacent the upper ends of the partitions; clips outstanding from the holders; the bottom being provided with elements coöperating with the clips in holding the articles which the device is to display.
- 20 3. A device of the class described comprising an outer, rotatably mounted case; a display member rotatable in the case and comprising a bottom and radially extended partitions defining a plurality of compartments in the display member; holders secured transversely to the outer edges of the partitions, to serve as partial closures for the compartments; and clips outstanding from the holders; the bottom being provided with elements coöperating with the clips in holding the articles which the device is to display.

2. A device of the class described comprising a base; a shaft rising therefrom; a case rotatable upon the shaft; a display member rotatable in the case and comprising a bottom, a tube rising from the bottom and inclosing the shaft, partitions secured to and radiating from the tube; holders disposed transversely of the partitions and secured 30 to the edges thereof, adjacent the upper ends of the partitions; clips outstanding from the holders; the bottom being provided with elements coöperating with the clips in holding the articles which the device is to display.

In testimony that I claim the foregoing as my own, I have hereto affixed my signature in the presence of two witnesses.

ROBERT H. REID.
